UNITED STATES PATENT OFFICE.

JACOB L. STAIR, OF ALTAMONT, ILLINOIS.

FURNITURE-BASE.

SPECIFICATION forming part of Letters Patent No. 558,854, dated April 21, 1896.

Application filed December 28, 1893. Serial No. 494,952. (No model.)

To all whom it may concern:

Be it known that I, JACOB L. STAIR, of Altamont, in the county of Effingham and State of Illinois, have invented a new and Improved 5 Furniture-Base, of which the following is a full, clear, and exact description.

The invention relates to articles of furniture, such as folding beds, bookcases, or combined articles, such as a bookcase and bed or 10 bookcase and wardrobe or the like, in which the supported article is so mounted on its base as to permit of the swinging of the article, when placed near a wall, without contacting with the wall; and the object of the 15 invention is to improve furniture-bases of this character in various particulars, as herein-after pointed out.

The invention is hereinafter described.

Reference is to be had to the accompanying 20 drawings, forming a part of this specification, in which similar letters of reference indicate corresponding parts in all the views.

Figure 1 is a perspective view of a base embodying my invention. Fig. 2 is a plan view 25 of the base, the article of furniture being indicated in dotted lines and the pivots of such article being shown in section. Fig. 3 is a similar view showing a different position of the parts. Fig. 4 is a transverse vertical section through the base and the lower end of a supported piece of furniture, and Fig. 5 is a 30 broken inverted plan view of the bottom of such supported article.

In constructing a base in accordance with 35 my invention the fixed part A is recessed in its upper surface, as at a, which recess extends to the front of the base and inward to about the center, and from the recess extends rearwardly a groove a'. In the recess thus 40 formed the sliding part or section B is fitted and provided with a tongue B', which is longitudinally slotted, as at B'', for a purpose presently to be explained, and extends from the rear edge of the slide B at the center and 45 fits in the groove a', the side walls a² a³ of the recess a and groove a' being undercut to receive and guide the reduced side edges b b' of the slide or movable part B, the arrangement 50 permitting a movement of the slide transversely of the fixed base A.

Stops C in the form of angle-irons are secured to the back edge of the slide B and con-

tact with the front rail a⁴ of the base A, thus limiting the outward movement of the part B, and the latter is formed at the front to 55 correspond with the finish of the base A.

In order to afford support for the tongue B' when drawn outward, the base A is formed with a forward extension a⁵ at the rear wall of the recess a, such projection being normally accommodated in the recess b², formed 60 in the inner edge of the slide B.

In the base A a cam-guide groove D is formed and ranges in a sweeping curve longitudinally of the base A, and this cam-groove 65 is sufficient in itself to permit a partial rotation of the supported article of furniture E; but it is preferably formed, in accordance with the present invention, continuous, with forwardly-extending branch grooves D', that 70 curve toward each other and are continued to and through the front edge of the base A. In the base thus constructed I mount the piece of furniture E, which has a central pivot F and end pins or guides G G', of which 75 the central pivot engages the slotted tongue B' and the end guides normally enter the cam-groove D, as indicated at g g', Fig. 2. With this construction it will be seen that with the piece of furniture E in the normal 80 position the slide or movable part B may be drawn outward to the position shown in Fig. 2 and the said piece of furniture may be partially or wholly rotated.

In the rotation of the supported piece of 85 furniture its central pivot will travel outward freely in the slot B'', while either one of its end guides G or G', according to the direction in which the article E is moved, traverses the guide-groove D, the other pin or guide G 90 or G' being free to escape from the branch groove D' it occupied, and the branch grooves will permit a complete revolution of the supported article when desired to completely reverse its position.

By providing for the sliding of the part B independently of the supported article the friction is greatly reduced. Thus it will be seen that were the outward movement of the slide effected only by the swinging of the supported article the side thrust would produce considerable friction between the side walls of the recess a and groove a' and the slide B and tongue B'. From Fig. 3, for instance, it

will be seen that the supported article in its swinging movement will engage by its central pivot the outer end wall of the slot B², and thereby move the slide outward; but the 5 friction caused by side thrust on the part B' is considerable. This may be avoided by first drawing out the slide, as above described.

The bottom E' of the supported article may be provided with a suitable number of casters 10 e to facilitate its movements. In some instances the article E may have only one end pin or guide G, in which case the branch grooves D' may be omitted. This arrangement would permit a movement of the article through an 15 arc of one hundred and eighty degrees to bring either of its sides to the front; but it would be necessary to turn the article in a predetermined direction in order to effect this change of position, and the complete rotation 20 in either direction, therefore, is a decided improvement over such partial rotation, as will readily be understood.

Having thus described my invention, I claim as new and desire to secure by Letters 25 Patent—

1. The combination, with a base having an outwardly-movable section and a longitudinal guideway, of a supported article thereon, pivotally engaging the base at its movable

section, and engaging the guideway of the 30 fixed section, said guideway having branches extending through the front of the base, whereby a complete revolution of the supported article is permitted, substantially as described. 35

2. The combination, with a base having an outwardly-movable section, and a longitudinal guideway which has end branches extending through the front of the base, of a supported article of furniture pivotally engaging at its 40 center with the base, at the movable section of such base, and engaging near each end with the guideway, substantially as described.

3. The combination, with a base provided with a transversely-sliding section, and having a guideway extending longitudinally of the base, the said guideway having end branches that curve toward each other and extend through the front of the base, of a supported article of furniture pivotally engaging 45 the sliding section of the base, the said article having engagement also with the guideway of the base, substantially as described. 50

JACOB L. STAIR.
